AUTOMATIC DUST BIN

Filed April 25, 1929

UNITED STATES PATENT OFFICE

ROBERT B. MCELROY AND FRANK ARTHUR ANDERSON, OF PORTLAND, OREGON

AUTOMATIC DUST BIN

Application filed April 25, 1929. Serial No. 358,014.

Our device relates to dust bins and has for its primary object the reception and retention of sweepings and the like, the same being made of metallic sheets having a hinged closure disposed adjacent the front wall thereof and having a bin or chute disposed adjacent to or forming the inner bottom wall of the body element.

The primary purpose and object of our device is to displace or replace dust pans and the like and is intended for placing within the wall at the mop board of the room into which the sweepings may be quickly deposited at the conclusion of the sweeping operation of the room.

A further object of our device resides in a simplified construction that may be used to conduct the sweepings from the various rooms to a central receptacle that may be disposed within the furnace or within the basement of the house or building in which the same are being used.

A further object of our invention is to provide a means that will speed up the sweeping operation without the use of dust pans and wherein the sweeping refuse may be deposited within a suitable receptacle or collected at a central station.

With these and incidental objects in view, the invention consists in certain novel features of construction and combination of parts, the essential elements of which are set forth in the appended claims, and a preferred form of embodiment of which is hereinafter shown with reference to the drawings that accompany and form a part of this specification.

In the drawings:

Fig. 1 is a perspective, sectional, side view of one of our devices shown installed within the base board or mop board of the room, illustrating the closure door closed.

Fig. 2 is a vertical, longitudinal, cross sectional view, of the device illustrating the closure door open and in locked position.

Fig. 3 is a fragmentary, sectional, front view of the assembled device.

Fig. 4 is a longitudinal, sectional, side view of the assembled device illustrating the door closure open and illustrating the dust collecting bin in condition for removal from the device.

Fig. 5 is an end view of the assembled device illustrating the door in closed position and also illustrating a construction that is adaptable for being used in conjunction with the sweeping box illustrating a chute leading from the device to a central station for the collecting of the sweepings.

Like reference characters refer to like parts throughout the several views.

1 is the joist or floor support upon which the floor 2 is placed and 3 and 4 are the side walls of a partition illustrating the space 5 disposed between the side walls 3 and 4. 6 is the base board or mop board and 9 is the mold running therealong and along the top side of the base or mop board.

We preferably form our device of sheet material. The body portion 10 has a finishing strip 11 which form top and side angle bars for the body element 10. A hinged closure 12 is hingedly supported upon a journaled pin 13, supported in oppositely disposed ends of the body portion 10. The hinging closure 12 is adapted to being actuated by the foot or hand of the sweeper or manipulated by the broom or sweeping implement. A locking bar 14 is hinged relative to the side wall about a hinging pin 15. One end 20 of the locking bar 14 passes through a slot 16 and protrudes therefrom so that it may be actuated by any suitable means. A locking notch 17 is disposed on the other end of the locking bar 14. The locking bar 14 is pivoted off-center upon the pin 21 so that the locking bar rides upon the pin 18 secured upon the hinged closure 12. When it is desired to maintain the closure 12 in an open position, the closure is swung back far enough

so that the locking notch 17 catches on pin 21 and by gravity the bar 14 stays in position until a downward pressure is applied to the protruding end 20; the closure then will return to that of the normal closed position through the action of gravity. An arcuate slot 19 is disposed within the side of the body element through which the pin 18 passes. The sides of the body element have inwardly extending edges 21B which act as supports for the dust bin 21 which is removably disposed upon the base of the body element, said bin having outwardly extending flaps 21C which ride on edges 21B.

15 Where a positive closure is desired an actuating spring 21A may be placed about the hinging pin 13 to snap the closure 12 shut. Where our device is to be installed in new construction, dust chutes or sweeping chutes 20 lead from the receptacle to a central collector disposed at a convenient location in the basement or running directly to the furnace so that the sweepings may be collected at a central station.

25 When it is desired to remove the sweepings the door is opened and the bin 21 is removed through the opening as illustrated in Fig. 4.

While the form of mechanism herein shown and described is admirably adapted to fulfill the objects primarily stated, it is to be understood that it is not intended to confine the invention to the one form of embodiment herein shown, as it is susceptible of embodiment in various forms, all coming within 35 the scope of the claims which follow.

What we claim is:

1. In a device of the class described, the combination of a metal body member, a closure hingedly secured to the body member, a pin outwardly extending from the closure and passing through an arcuate slot disposed in the side wall of the body member, a locking bar rockably mounted relative to the body element and outwardly extending through the side wall of the body element, said locking bar having a notch disposed in one edge, said locking bar resting upon the pin outwardly extending from the closure and said notch being in registerable alignment with the pin to maintain the closure in an open position when thus engaged.

2. In a device of the class described, the combination of a body element, a hinged closure disposed in the front wall of the body element and held normally closed, a projection outwardly extending from the closure and passing through an arcuate slot disposed in the side wall of the body element, a locking bar resting upon the projection and a notch disposed in the locking bar to maintain the closure open when the notch engages the projection.

3. In a device of the class described, the combination of a body element having a removable bottom, a closure hingedly secured

to the front wall of the body element and maintained normally closed, the closure having a locking pin outwardly extending from one of the edges of the closure and passing through the end opening in the side wall, a locking bar resting upon the pin and having a notch disposed in the edge of the bar engaging the pin and when said notch engages said pin the notch locking the pin to maintain the closure in an open position and means for unlatching the bar from the pin from the exterior of the body element.
